UNITED STATES PATENT OFFICE

105,767

DESIGN FOR A COMBINED RULER AND PENCIL CASE OR SIMILAR ARTICLE

Ernest Steiner, New York, N. Y.

Application April 1, 1937, Serial No. 68,509

Term of patent 14 years

To all whom it may concern:

Be it known that I, Ernest Steiner, a citizen of the United States and residing at New York city, in the county of New York and State of New York, have invented a new, original, and ornamental Design for a Combined Ruler and Pencil Case or Similar Article, of which the following is a specification, reference being had to the accompanying drawing, forming part thereof, and in which

Fig. 1 shows a front perspective view of the combined ruler and pencil case.

Fig. 2 shows a rear perspective view of the combined ruler and pencil case.

Fig. 3 shows a front perspective view of the combined ruler and pencil case partly open.

Fig. 4 is an end elevational view of the combined ruler and pencil case.

Fig. 5 is a fragmentary perspective view of the combined ruler and pencil case with one of its compartments open to receive or permit removal of a pen, pencil, eraser, or similar device.

The principal characteristics of the design are the plurality of connected sections movable relative to each other, said sections forming container elements for receiving pens, pencils, erasers, and so forth in combination with the provision of a ruler on a side of one of the outer sections.

I claim:

The ornamental design for a combined ruler and pencil case or similar article as shown and described.

ERNEST STEINER.
